ALARM CIRCUIT

Harry Campbell Grant, Jr., New York, N. Y., assignor to Walter Kidde & Company, Inc., New York, N. Y., a corporation of New York

Original application November 21, 1929, Serial No. 408,740. Patent No. 2,003,358. Divided and this application November 10, 1931, Serial No. 574,092. Renewed December 3, 1936

4 Claims. (Cl. 177—355)

The present application is a division of applicant's copending application Ser. No. 408,740 for System for indicating the presence and location of fire, filed November 21, 1929, now Letters 5 Patent No. 2,003,358 dated June 4, 1935, and relates to that portion of the system shown and described in the above copending application which includes the alarm circuits for actuating an alarm mechanism upon the existence of a 10 disorder in the alarm system or the actuation of an alarm initiating mechanism.

More particularly, the invention embodies an improved alarm system wherein supervising alarm mechanism is utilized in connection with 15 a general alarm mechanism, means being provided to disconnect the supervising alarm and prevent its actuation upon the actuation of the general alarm mechanism. In this fashion, the 20 functions of the supervising or trouble alarm mechanism and the general alarm mechanism are isolated and a correct indication given as to the nature of a disturbance in the alarm system.

An object of the invention, accordingly, is to provide an alarm system wherein a general alarm, 25 as well as a trouble alarm are utilized, means being provided to isolate the function and operation of these two alarms whereby each will properly respond only to the particular conditions 30 which it is desired that the respective alarm mechanisms shall actuate.

A further object of the invention is to provide an improved alarm mechanism of the above character wherein a supervising relay is provided for controlling the actuation of trouble alarm 35 mechanism, such relay being adapted to be short circuited upon the existence of a condition which actuates the general alarm, further means being provided to open the circuit of the trouble alarm mechanism upon the short circuiting of the said 40 relay to prevent operation of the trouble alarm mechanism upon such condition.

Further objects, not specifically enumerated 45 above, will be apparent as the invention is described in greater detail in connection with the accompanying drawings, wherein:

Figure 1 is a wiring diagram showing schematically a fire detecting system constructed in accordance with the present invention.

Figures 2 and 3 are diagrammatic views showing 50 the system of Figure 1 enlarged.

At the outset, the general detecting and signaling system in connection with which the present alarm system is used will be described in order 55 that the present invention may be more fully understood and its scope appreciated.

Referring to the above drawings, a battery is indicated at BAT, having its positive terminal connected to a positive bus wire 1 which includes a battery supervising relay 2, a switch S₀ having switch points 3 and 4, connections 5 and 6, switch 5 S_m having switch points 7 and 8, and positive bus wire 9. A plurality of external circuits, in which thermostats or other suitable heat operated devices are connected, is used in connection with the system shown and described herein, but for 10 the purposes of description and in the interest of clarity, only two such circuits have been shown. These circuits have been marked as A and B and one side of each of these circuits is connected to the positive bus wire 9. Since the 15 circuits A and B are identical and are connected to similar relays and associated elements, only the connection for circuit B will be described herein, it being understood that the corresponding elements of circuit A, as well as other circuits, 20 not specifically shown, function in the same manner as the elements of circuit B. The other side of each external circuit is connected to the negative terminal of the battery and the elements for so connecting these circuits include, in the case 25 of circuit B, a wire 16, a contact 17, a trouble alarm relay T₁, a fire alarm relay M₁, wire 18, wire 19, and negative bus wire 20, such negative bus wire being connected to the negative terminal 30 of the battery.

It will thus be seen that a supervisory current flows through the external circuit, the trouble alarm relay T₁ and the fire alarm relay M₁. If a break should occur in the wire so that current 35 through the trouble alarm relay T₁ is interrupted, this relay will be deenergized and will close contacts 21 and 22, causing a trouble alarm lamp L₁ to be lighted. Current flows through the trouble alarm lamp L₁ from the positive bus wire 9 through the lamp, contact 21, to connection 23, contact 24, and connection 25 to the negative bus wire 20. This light indicates trouble in the 40 external circuit B. At the same time, the general trouble alarm bell T_B is sounded since it is connected to the positive bus wire through wire 10, point 26, point 27, point 28, point 29, through the bell T_B, point 30, wire 32, points 33, 35, and 37, contact 22, contacts 38 and 39 of switch S₁, point 23 through contact 24 and point 25, 50 to negative wire 20. In order to clear the general trouble alarm bell so that it may be free to indicate trouble in other circuits, the switch S₁ is thrown to the left to make contact at point 40, thus opening the circuit through the general trouble alarm bell and clearing the bell for the 55

indication of trouble in the other circuits. The trouble alarm lamp L_1 remains lighted until the trouble has been repaired whereupon the trouble alarm relay T_1 picks up its armature thus opening the contacts 21 and 22. The trouble alarm lamp L_1 remains lighted, however, by reason of its connection from the positive wire 9 to the successive points 40, 39, 23, 24, and 25, the latter of which is on the negative wire 20. In order to clear the trouble alarm lamp L_1 , the switch S_1 is thrown to its normal position at the right, as viewed in the figure, to make contact at point 38, thus opening the circuit through the trouble alarm lamp L_1 just described.

15 The battery supervising relay 2 is in series with the circuit supplying current to the external circuits and if the current from the battery should fail, the battery supervising relay 2 will be deenergized and close contacts 41 and 42, thus causing the battery supervising trouble alarm lamp L_2 to be lighted and the general trouble alarm bell T. B. to be sounded. Current flows through the trouble alarm lamp L_2 from the positive bus wire 9 through wire 10, points 26, 27, 72 and 301, 25 through the lamp L_2 , contact 41, and point 302 to the negative line at point 303; while the path of current through the general trouble alarm bell T. B. is from the positive bus wire 9 through wire 10, points 26, 27, 28 and 29, through the 30 general trouble alarm bell T. B., points 30 and 304, contact 42, switch S_7 , and point 302 to the negative line at point 303. The switch S_7 is provided to clear the general trouble alarm bell in the same manner as that described in connection 35 with the trouble alarm relay T_1 .

Two fire alarm bells are provided, one supervised and one unsupervised. The supervised fire alarm bell is indicated at S. A. while the unsupervised bell is indicated at U. A. The supervised 40 bell is in series with a relay 43 which is of such resistance as to prevent the ringing of the supervised fire alarm bell, at the same time permitting a supervisory current to flow. The supervisory connection is from the positive wire 9 to the 45 successive points 26, 27, and 28, through the supervised fire alarm bell to the point 44, through the winding of the relay 43 and connection 45 to the point 46 on the negative bus wire 20. If the supervised alarm bell should become inoperative, the supervising current will fail and the relay 43 will become deenergized, thus permitting the closing of its contacts at 47 and 48, thus lighting the supervised-fire-alarm-bell-trouble-alarm lamp L_3 and sounding the general trouble 50 alarm bell. Current flows through the trouble alarm lamp L_3 from the positive bus wire 9 through wire 10, points 26, 27 and 72, through the lamp L_3 , contact 47, point 73, wire 74 and contact 69 to the negative line; while the path 55 of current through the general trouble alarm bell T. B. is from the positive bus wire 9 through wire 10, points 26, 27, 28 and 29, through the general trouble alarm bell T. B., contact 48, switch S_6 , point 73, wire 74 and contact 69 to the negative line. The switch S_6 is provided for clearing 60 the general trouble alarm bell in the same manner as that described in connection with the trouble alarm relay T_1 .

A fuse 221 will be found in one lead to the 70 supervised fire alarm bell. The reason for installing this fuse is that the resistance of the winding of the supervised fire alarm bell is ordinarily only a fraction of one percent of the resistance of the winding of the fire alarm bell supervising relay 43. If a short circuit of the

supervised fire alarm bell leads should occur, no trouble signal would be given because the short circuit of the winding of the supervised fire alarm bell would allow a slightly greater supervising current to flow through the supervising relay, this increase in current not being, however, great enough to blow the fuse 221. If a fire signal should be given, at which time the high resistance of the supervised fire alarm bell supervising relay is cut out of the circuit, the short circuit 10 of the fire alarm bell connecting wires would constitute a direct short circuit across the source of current and, therefore, the fuse 221 is placed in one lead to the supervised fire alarm bell to relieve, immediately, this short circuit condition 15 which otherwise would seriously affect the operation of the other circuits of the system. The blowing out of this fuse places the system in a condition to render a delayed trouble signal in a manner to be described hereinafter. 20

In order that this condition be assured, it is essential that the fuse 221 be of a lower rating than the main battery and main power supply fuses, so that the fuse 221 will blow first, as otherwise the system would be rendered inoperative. In fact, the normal current passing through each of the main fuses must be allowed for, so that the short-circuit current added to the normal current is not sufficient to blow a main fuse before the fuse 221. 25

A resistance 49 is connected in the external circuit B at the extreme end thereof and the resistance is of such value as to limit the current which flows through the trouble alarm relay T_1 and the fire alarm relay M_1 to a value below that 30 necessary to cause the fire alarm relay M_1 to pick up. If, however, by reason of a fire in one of the spaces protected on the circuit B, a thermostat should function and thus short circuit the 35 resistance 49, sufficient current will flow through 40 the circuit already described and cause the fire alarm relay M_1 to pick up its armature and close contacts at points 50, 51, 52, and 53, at the same time breaking the contacts at the points 17 and 24. The fire alarm relay M_1 is so constructed that 45 the contact 51 will make before the contact 17 breaks. The purpose of contact 17 is to connect the resistance of the external circuit across one portion of a Wheatstone bridge as described hereinafter. 50

The opening of the contact 17 would result in the deenergization of the fire alarm relay M_1 were it not for the closing of contact 51 before the opening of contact 17. By reason of the closing of the contact 51, a connection is made through the 55 winding of the fire alarm relay M_1 from the positive bus wire 9 through conductor 141 to the successive points 54, 55, 56, 57, wire 58, connection 59, wire 60, connection 61 through contact 51, the winding of fire alarm relay M_1 , wires 18 and 19, 60 to the negative bus wire 20. The fire alarm relay M_1 , therefore, remains energized until the circuit through its winding is manually opened in the manner described hereinafter.

Upon the closing of contact 52, a relay 62 is 65 energized by reason of its connection to the positive bus wire 9 through wire 10, and connection 26, cabinet door switch C. D. S. and to the negative line through point 63, wire 64, through the contact 52, to the point 25. Upon energization of 70 the relay 62, contacts 66, 67 and 68 are closed, while contact 69 is broken. The closing of the contact 68 short circuits the supervised fire alarm bell supervising relay 43 and permits the supervised fire alarm bell to sound by reason of its 75

connection from the positive wire to the successive points 26, 27, and 28 through a wire 10 to the point 44, through a wire 71, through contact 68, to the point 45, and thence to the point 46 on the negative line. By reason of the short circuiting of the supervised fire alarm bell supervising relay 43, the relay 43 is deenergized and the contacts 47 and 48 are closed. This would cause trouble alarm lamp L₃ to light and the general trouble alarm bell to sound if it were not for the fact that the contact 69 of the relay 62 opens the connection from the trouble alarm lamp and from the general trouble alarm bell to the negative line. It will be seen that the trouble alarm lamp circuit 15 is from the positive wire 9 to the successive points 26, 27, 72 through the trouble alarm lamp and contact 47 to a point 73 (where the line from the general trouble alarm bell joins a common return 74), through such common return to the contact 69 20 and the negative line wire.

The unsupervised fire alarm bell U. A. is caused to ring at the same time as the supervised fire alarm bell, the circuit for accomplishing such ringing being closed through the contact 67. 25 Current flows from the positive wire 9 to the successive points 26, 27, 28, and 29, through the unsupervised fire alarm bell U. A. and through contact 67 to the negative line. Closing of the contact 66 produces an operation which will be 30 described more fully hereinafter.

External circuit fire alarm lamps A', B', C', D', E', F', G', H', I', J', K', etc. corresponding to the external circuits A, B, etc. are connected in series with a supervising relay 75. The supervising current flows through a circuit from positive wire 9 through a wire 111 to a connection 76, through a wire 126 to a connection 77, through contact point 78 to connections 79, 80, wire 81, connections 82 and 83, contact point 84, connections 85 and 86, wire 81, connection 88, contact 89, connection 90 and wire 91, connections 92 and 93, contact 94, connections 95 and 96, wire 97, connection 98, contact 99, connection 100, wire 101, connections 102 and 103, wire 104, relay 75, connection 105 and wire 106 to negative wire 20. Since the external circuit fire alarm lamps are in series, if any of the lamps become defective, the supervising current will cease and the relay 75 will be deenergized, closing its contacts 109 and 50 110. Closing contact 109 establishes a connection from the positive wire 9 through wire 111 to point 76, through the trouble alarm lamp L₄, through the contact 109, point 112, through wire 113 and contact 114 to wire 115 and the negative wire 20. At the same time, connection is established from the positive wire 9 to the successive points 26, 27, 28, and 29 through the general trouble alarm bell to the point 30 through the wire 32 and point 33, wire 116 to contact 110 and point 60 117, through switch S₁₀ to point 112 and negative wire as described above, thus causing the sounding of the general trouble alarm bell. The switch S₁₀ is provided for clearing the general trouble alarm bell in the manner already described in 65 connection with the trouble alarm relay T₁.

At the same time that a fire alarm relay, for example, M₁ is energized with consequent energization of the relay 62, a relay 118 is energized by reason of its connection from the positive wire through the wire 111 to the points 76 and 77, through the winding of the relay 118 to a point 119 and through a wire 120 to the point 63 which is connected to the negative line through wire 64, contact 52 and point 25. Upon 75 energization of the relay 118, the contacts at

78, 84, 89, 94, 99 and 114 are broken, while contacts are closed at 121, 122, 123, 124, and 125. The external circuit fire alarm lamp B', corresponding to the external circuit B, is then lighted by reason of its connection from the positive 5 wire 9 through the wire 111 to the point 76, through wire 126 to point 77, through contact 121 to point 80, through wire 81 to point 82, through contact 122 to point 127, through contact 123 to point 128, through contact 124 to point 129, through contact 125 to point 102, through wire 101 and fire alarm lamp B' to point 100, through wire 131 to contact 53, and to connection 25 on the negative line. The reason that the deenergization of the relay 75 does not result in lighting the trouble alarm lamp L₄ and ringing the general trouble alarm bell upon the breaking of the contacts at 78, 84, 89, 94, 99, and 114 is that the contact 114 is in the line which connects the trouble alarm lamp L₄ and 20 the general trouble alarm bell to the negative line. When the contact 114 is opened, the trouble alarm lamp L₄ and the general trouble alarm bell cannot function.

The foregoing description has dealt chiefly 25 with the various means for indicating trouble and with the means for indicating the particular circuit from which a fire signal has been given. It will be seen that the foregoing construction 30 will function equally well regardless of the number of external circuits and the corresponding fire alarm lamps which are connected therewith. The following description is concerned principally with the means for detecting the exact thermostatic circuit closer which has functioned in 35 the particular external circuit.

A Wheatstone bridge connection is provided including resistance elements 133 and 134, the resistance of the external circuit which has been 40 actuated, and a variable known resistance indicated generally at 137. Point 132 of this connection corresponds to the connection of the resistance elements to the negative side of a battery circuit while point 136 is the connection to a galvanometer and the unknown resistance which 45 is the resistance of the external circuit. Point 135 is the connection to the other side of the galvanometer and to one terminal of the variable known resistance 137. It will be seen that point 132 is connected through a resistance 138 to points 139, 140, wire 141, contact 240, contact 241 to the negative wire 20.

Point 135, on the other hand, is connected to the positive line through wire 144, resistance 145, movable contact 146, point 147, wire 148, resistance 149, and point 150 to a movable contact 151 and point 152 through wire 153 which is connected to the positive line through point 154 and wire 155 to point 54 and positive wire 9. One side of the external circuit B is connected 60 to the positive line and the other side of the circuit B, upon energization of the fire alarm relay M₁, is connected to the point 136 through wire 16, contact 50, point 156, wire 157, point 158, wire 159 and point 136.

Upon the occurrence of fire in any space, the fire alarm relay, corresponding to the circuit by which such space is protected, is energized. A fire alarm lamp indicating the circuit is lighted 70 and the fire alarm bells are sounded. The resistance of that portion of the external circuit lying between the positive line and the particular thermostat which has functioned, is brought 75 into proper relation with the Wheatstone bridge 75

- arrangement for permitting the automatic balancing of the resistance of the external circuit and the consequent determination of the particular thermostat which has functioned. The 5 variable resistance 137 consists of a rotary switch such as is now employed in automatic telephone work, resistances being connected between each of the adjacent points of the rotary switch.
- 10 With reference to the external circuit B, it will be seen that the path of the supervisory circuit from the positive wire 9 is through a compensating resistance 160, a resistance U₁, the terminal of a thermostat TT₁, a resistance U₂, through the terminal of a thermostat TT₂, etc., there being similar resistances before each thermostat. With reference to the variable resistance arrangement 137, the resistance 149 is of the same value as the resistance U₁; and the 15 resistances R₂, R₃, R₄, etc., are of the same values as the corresponding resistances U₂, U₃, U₄, etc., all of the resistances being of the same value. If, therefore, the contact 146 is moved from the 20 first point of the rotary switch to any other point, there can be cut into the Wheatstone bridge arrangement, enough resistance to balance the resistance from the external circuit which is thrown in as another leg of the Wheatstone bridge arrangement.
- 25 30 The automatic balancing of the resistance of the external circuit is accomplished through the medium of the Wheatstone bridge arrangement in combination with a galvanometer relay, the relay being so connected to the circuit that its contact remains closed as long as the balancing 35 resistance 137 is less than the resistance of the external circuit. It will be seen that the variable resistance 137 has been shown with the movable contact 146 on the first point of the 40 rotary switch. This is the normal position of rest at which time only the resistance 149 is in the balancing resistance circuit so that the resistance is always less than the resistance thrown in from the external circuit (except for the first resistance, which will be discussed later on). If, 45 therefore, any thermostat beyond the first one functions, a resistance greater than the balancing resistance will be thrown across the proper leg of the Wheatstone bridge, and the galvanometer 50 relay contact 161 will be closed.
- 55 As soon therefore, as a fire alarm relay, such as M₁ is energized, a relay 162 is energized by reason of its connection from the positive wire 9 through the connection 54, line 155, connection 154, wire 153, connection 163, wire 164, contact 165, wire 166, through relay 162, galvanometer contact 161, wire 141, contact 240, contact 241 to the negative wire 20. When the relay 162 is energized, the contact 171 is closed. This results 60 in energizing relays indicated as Mot. 1 and Mot. 2, by reason of their connection with the positive wire 153 through the motor relay windings, the parallel relay contacts 243 and 244, respectively, wires 245' and 245'' and connection 245, wire 246, connection 247, contact 171, connection 105 and wire 106 to the negative line wire 20. Upon 65 the closing of the contact 171 of the relay 162, connection is established from the positive line to the negative line. The slow acting relay 237 is thus energized and contact 165 opened, thus de-energizing relay 162 so that contact 171 is opened and slow acting relay 237 deenergized. This cycle of operation is repeated as long as the galvanometer contact 161 is closed. At the same time 70 75 that the slow acting relay is deenergized by the

opening of the contact 171 or the relay 162, the motor relays Mots. 1 and 2 are deenergized and simultaneously with the deenergization of the motor relays, the movable arm 146 moves one step from the first to the second point of the rotary switch. The same cycle is repeated until the amount of the balancing resistance 137 which has been cut in, is equal to, or greater than, or even somewhat less than, the cut-in portion of the resistance of the external circuit. As soon as this condition is reached, the current flow through the galvanometer winding either weakens sufficiently, ceases, or reverses, so that the galvanometer contact 161 is broken, as well as the circuit through the relay 162. The rotary 15 switch has therefore come to a position of rest and can be made to indicate the exact thermostat which has functioned. This will be described in greater detail hereinafter. While in a theoretically perfect circuit the balancing resistance can 20 be considered as exactly balancing the resistance of the external circuit, the resistance of the external circuit might be somewhat less than the proper balancing resistance due to slight negative errors in winding the resistance units U₁, U₂, etc., while it might be somewhat more than the proper balancing resistance due to more wiring being used in the external circuit than the theoretically correct amount. The galvanometer relay is therefore adjusted to operate over a range 30 such that the correct balancing resistance will be cut in not only when the resistance of the external circuit equals the proper balancing resistance, but also when it is within predetermined negative and positive variations from the proper 35 balancing resistance.

On the assumption that the first thermostat has functioned, the lamp O of the tens column and the lamp 1 of the units column will be lighted in the following manner. The positive line wire 40 9 is connected to all of the lamps of each column and current flows through the proper lamp, in the hypothetical instance the lamp O, of the tens column to point 174, through a movable contact 175, connection 176, wire 177, and wire 143 to 45 the connection 119, wire 120 and connection 63 to wire 64, and contact 52 to connection 25 on the negative line. At the same time, current flows from the positive wire 9 through the units lamp 1, wire 179, movable contact 180, and through 50 the connection 176 and path just traced. The connection of the points in the fifth row is such that a single set of lamps will serve for the unit indications, while the connection in the fourth row is such that one lamp is required for each 55 of the tens of the series of thermostats and balancing resistances.

Relay 237 is a very slow acting relay to permit motors 1 and 2 to complete, with certainty, a cycle of operation before a new cycle is instituted. 60 As before described, when galvanometer contact 161 is closed, connection is established from the positive line at 163, through contact 165, wire 166, relay 162 and galvanometer contact 161 to the negative line. Relay 162 is thus energized and 65 contact 171 closed so that connection is established from the positive line at 228, through the winding of the relay 237, through contact 171 and to the negative line. The relay 237 is thus energized and contact 165 opened thus deenergizing relay 162 so that contact 171 is opened and relay 237 deenergized. This cycle of operation is repeated as long as the galvanometer contact 161 is closed. Each time that contact 171 is closed, connection is established from the positive 70 75

line through the windings of the motor relays 1 and 2 through parallel contacts 243 and 244, connection 245, wire 248, to the point 247 and through contact 171 to the negative line, thus energizing Mots. 1 and 2. As already explained relay 237 is very slow acting and thus serves to insure complete operation of both motor relays 1 and 2 before relay 237 opens the contact at 165. Such opening results in the deenergization of relay 162 and the opening of contact 171, which results in the deenergization of the motor relays 1 and 2 and of the slow acting relay 237.

In order to reset the system, the push button switch 194 is operated to make contact with the point 192. Breaking the contact at 55 causes the deenergization of the fire alarm relay M1 with the consequent return to normal conditions of the apparatus controlled thereby. Connection is thus established from the positive line at 54 to the point 192, through wire 250 to connection 251, through the windings of relays 252 and 253, to points 254 and 255, to the interconnected points of the two rotary switches through wires 254' and 255'. From these respective interconnected points, the circuit is completed to the negative line through points 235 and 236. The relays 252 and 253 are therefore energized, causing the respective contacts at 241 and 243 for the relay 252, and 240 and 244 for the relay 253 to be broken and contacts 266 and 257, to be closed for the relay 253, while the corresponding contacts are closed for the relay 252. With the closing of the contacts 256 and 257, connection is established from the positive line 153 through points 152 and 232, through contact 257 and line 250, to the point 251, through the windings of the relays 252 and 253 to the points 254 and 255 to the interconnected points of the rotary switches and thus to the negative line. Even though the push button switch 194 is returned to its normal position in contact with point 55, the relays 252 and 253 remain energized until such time as movable contacts 191 and 198 rest upon the first points of the respective rotary switches. Through the closing of the contact 266 of the relay 253, connection is established from the positive line through the motor relay 2, through the contact 266, contact 169, to the interconnected points of the rotary switch and thus to the negative line. Corresponding action occurs for relay 252 and results in energization of the motor relay 1. At the same time, contact 169 is opened and the motor relay 2 is deenergized, causing the advance of the rotary switch one step. After such advance, the contact 169 is again closed and the motor relay is again energized. Such operation continues until the movable contact 191 rests upon the first point of the rotary switch. If, for any reason, motor 2 should get out of step with motor 1, motor 2 will not continue to operate its rotary switch but will come to rest because it is no longer energized after the movable contact 191 rests upon the first point of the rotary switch. Motor 1 is therefore free to return the other rotary switch to its initial position without being affected by the action of motor 2.

The switch 208 is a push button switch similar to the push button switch 194 and interconnected with the switch 194 in a series parallel arrangement, and is controlled by the opening of the door of the cabinet in which all of the apparatus is arranged. Upon the occurrence of fire, the fire alarm bells sound and the system automatically balances itself. The fire watch attendant then runs to the central station and opens

the door of the cabinet, thus causing the switch 208 to momentarily close the circuit from the point 56 to the point 193, causing a resetting action to occur in the same manner as caused by the push button switch 194. As soon, however, as the movable contacts reach the first switch points, the fire indication is repeated and the fire watch attendant can determine from the lamps which are lighted the space which is afire. He can then push down the manual reset push button 194 and reset the system, and when the movable contacts again reach the first switch points the fire indication will be again given as a check upon the initial reading. This resetting operation can be made as many times as the fire watch attendant desires in order to be sure that the apparatus has functioned properly and that the proper space has been indicated.

After the fire has been extinguished and the thermostat has been renewed, the door of the cabinet can be closed and the system will again be in its normal condition. If it should be forgotten to reset the system by means of the manual push button 194, the closing of the door will accomplish the resetting action through the closing of the push button switch 208.

Compensating resistances 160 and 209 may be inserted at predetermined intervals in the external circuits while compensating resistance 145 may be inserted before the movable contact 146 to correspond with the resistance 160, while compensating resistance 210 may be inserted between the fourteenth and fifteenth contacts in the second row of contacts to correspond with the resistance 208.

A door switch C. D. S. is provided in the circuit of the fire alarm bell ringing relay 62, so that upon the opening of the cabinet door the fire alarm bells will stop sounding. If, however, the cabinet door is closed before the short circuited thermostat has been restored with a new, open circuited thermostat, the bell will again ring and indicate the failure to restore the thermostat. Attempting to reset the apparatus without restoring the thermostat will merely result in the repetition of the fire signal.

If on the other hand, the cabinet door is left open, as it should be until the thermostat has been restored and if the thermostat is removed from the line (the thermostats are not bridged across two continuous wires, but the external circuit wires are run in sections between the thermostats, and the thermostats are designed so that when removed, they break both sides of the external circuit and thus initiate a trouble signal), the trouble signal will not be given because the fire alarm relay has remained energized and the trouble circuit has been disconnected, but the wire break left by the removal of the thermostat constitutes an infinite resistance thrown across one leg of the Wheatstone bridge, and the arm of the rotary switch advances to the last point of the balancing arrangement when an infinite resistance is then thrown in to balance the infinite resistance of the open external circuit. When the thermostat has been restored, the arm of the rotary switch still rests on the last point because the current limiting resistance in the external circuit is great enough to require the infinite resistance to balance it, no other balancing resistance being available. All during this time the external circuit fire alarm lamp has remained lighted. If now the cabinet door is closed, the reset button operated by the closing action of the door will cause the fire alarm relay to be de-

energized and the system to be restored to its normal condition, the rotary switch arm advancing to the first point. If on the other hand, someone should close the cabinet door between the time the short circuited thermostat was removed and a new thermostat installed, the fire alarm signals will be cleared immediately, and the trouble signal will be given. If, still further, a thermostat should be removed from an external circuit, the condition of the system being initially normal (for example, no fire signal has been previously given), the trouble signal will be immediately given, indicating a wire break.

Reference has been made hereinbefore to the use of a fuse 221 in the supervising circuit of the supervised fire alarm bell for the purpose of preventing the failure of the system due to a short circuit of the supervised fire alarm bell. As previously described, the fuse 221 is designed to blow out at the time that a fire signal is given. As soon as the cabinet door is opened to stop the sounding of the fire alarm bells, the bell ringing relay 62 is deenergized and the circuit through the trouble signal is closed so that the delayed trouble signal hereinbefore referred to is thus given, together with the fire signal.

In the explanation given at the beginning of this description, the battery was pointed out as the source of energy for furnishing the supervising current. This reference was made for simplification of the description. In reality the battery is under trickle charge, the actual current normally supplying the supervising current to the positive line 9 being obtained directly from the power supply terminals indicated to the right of the battery terminal. The normal path of the supervising current is from the positive terminal 212 of the power supply to the point 213 through the contact 214 through the successive points 215, 216, and 217, through the wire 218, through the contact 219, through the successive points 5, 6, 7, and 8 and then through the external circuits back to the negative line in the manner already described. It will be noted that the contact 219 short circuits the resistance 220.

The path of the battery charging current is from the positive terminal 212 of the power supply to and through the successive points 213, 214, 215, 216, and 217, through the contact 219, to and through the successive points 5, 4, and 3, through the winding of the relay 2, to the positive terminal 1 of the battery, and then to the negative line.

It so happens that when the fire alarm bells are sounding, a much greater current is required from the power supply, and the tendency would be for the voltage across the system to decrease below the battery voltage. In order to prevent such decrease, a portion of the resistance in the power supply circuit is cut out. This resistance is shown at 223 and is short circuited by the closing of the contact 66 of the bell ringing relay 62.

On the other hand, if the battery should for any reason go off the line, a smaller current would be drawn from the power supply, and the tendency would be for the voltage across the system to increase. In order to prevent such increase, additional resistance must be added to the power supply line. This resistance is shown at 220, and is added by the removal of the short circuit at the contact 219 of the battery supervising relay 2, which is deenergized upon the failure of the battery, with the result that the contact 219 is opened.

75 The power supply is supervised by the relay 224

which is deenergized upon the failure of the power supply, causing the contacts 225 and 226 to be closed, at the same time opening contact 214 in order to prevent the discharge of the battery back through the circuits which may also be connected across the power supply. The closing of the contact 225 results in the lighting of the trouble alarm lamp L₆ and the closing of the contact 226 results in the sounding of the general trouble alarm bell. The switch S₆ is provided to clear the general trouble alarm bell, in the manner already described in connection with the trouble relay T₁.

From the foregoing description, it will be apparent that a fire detecting system is provided embodying a minimum of wiring, the system being completely supervised against wire breaks, power supply trouble, battery trouble, external circuit alarm trouble, and external circuit fire alarm lamp trouble. A single general trouble alarm bell may be employed which may be readily cleared at all times for the indication of trouble in other circuits. The trouble alarm lamps will remain lighted until the trouble has been repaired and until the trouble alarm lamp switches have been returned to their normal positions, and the system is capable of indicating exactly the location of a fire, either through manual balancing means, or automatic balancing means. The system provides for checking the results rendered either manually or automatically, and permits the checking of the restoration of the thermostat that has functioned since the system cannot be returned to its normal condition unless the thermostat is restored. Variations in the resistance of the external circuits due to variations in wiring can be easily compensated for and the apparatus is capable of being arranged in a single cabinet with an appropriate door switch so that the sounding of the fire alarm bells can be stopped by the opening of the cabinet door and so that the fire must be attended to and the thermostat replaced before the cabinet door can be closed again without the repetition of the fire signal. In the event that the system is not properly reset, the closing of the cabinet door can be made to operate a resetting switch.

While the invention has been described with specific reference to the accompanying drawings, it is not to be limited, save as defined in the appended claims.

I claim as my invention:

1. In an electric alarm system of the type comprising a normally inactive alarm circuit, a source of electrical potential for energizing said circuit, a fuse in at least one of the main supply leads from the source of electrical potential, an alarm having a pair of leads subject to short-circuiting in use, an alarm supervising relay, connections to connect said alarm, said leads, said alarm supervising relay and said source of electrical potential in a series circuit, whereby a supervisory current of limited value flows through said series circuit, an alarm actuating relay controlled by said alarm circuit, and a normally open contact controlled by said alarm actuating relay and arranged to short-circuit said alarm supervising relay upon closing of said contact upon said alarm circuit being actuated; the provision of means for enabling an alarm to be rendered despite short-circuiting of the alarm leads and consequent short-circuiting of the source of electrical potential, said last named means comprising a second alarm adapted to be controlled by a normally open contact of said alarm actuating relay, and a fuse in said series circuit through the first named alarm of 75

- lesser rating than a main supply fuse, whereby said last named fuse is adapted to open said series circuit through the first named alarm upon short-circuiting of the leads thereof and ensuing actuation of said alarm circuit and to thereby remove the resulting short-circuit of the source of electrical potential without blowing a main supply fuse, thereby leaving the alarm system in condition to render an alarm through said second named alarm.
2. In an electric alarm system of the type comprising a normally inactive alarm circuit, a source of electrical potential for energizing said circuit, a fuse in at least one of the main supply leads from the source of electrical potential, an alarm having a pair of leads subject to short-circuiting in use, a relay controlled by said alarm circuit, and a contact controlled by said relay and arranged to control an alarm operating current in a series circuit including said alarm, said leads and said source of electrical potential upon said alarm circuit being actuated; the provision of means for enabling an alarm to be rendered despite short-circuiting of the alarm leads and consequent short-circuiting of the source of electrical potential, said last named means comprising a second alarm adapted to be controlled by a normally open contact of said relay, and a fuse in said series circuit through the first named alarm of lesser rating than a main supply fuse, whereby said last named fuse is adapted to open said series circuit through the first named alarm following short-circuiting of the leads thereof and to thereby remove the resulting short-circuit of the source of electrical potential without blowing a main supply fuse, thereby leaving the alarm system in condition to render an alarm through said second named alarm.
3. In an electric alarm system of the type comprising a normally inactive alarm circuit, a source of electrical potential for energizing said circuit, a main alarm, a main alarm supervising relay, connections to connect said main alarm, said main alarm supervising relay and said source of electrical potential in a series circuit, whereby a supervisory current of limited value flows through said series circuit, a trouble alarm, a normally open contact controlled by said main alarm supervising relay, connections to connect said trouble alarm, said normally open contact and a source of electrical potential in a normally open series circuit, a main alarm actuating relay controlled by said alarm circuit, and a normally open contact controlled by said main alarm actuating relay and arranged to short-circuit said main alarm supervising relay upon closing of said last named contact upon said alarm circuit being actuated; the provision of means for preventing operation of the trouble alarm, due to short-circuiting of the main alarm supervising relay, concurrently with the operation of the secondary alarm, said last named means comprising a normally closed contact controlled by said main alarm actuating relay and arranged in the normally open series circuit through the trouble alarm.
